BEVERAGE POT

John N. Polivka, Minneapolis, Minn., assignor to General Mills, Inc., a corporation of Delaware

Application August 7, 1950, Serial No. 11,666

Term of patent 14 years

(Cl. D44—29)

To all whom it may concern:

Be it known that I, John N. Polivka, a citizen of the United States, residing at 2418 Northeast California, city of Minneapolis, county of Hennepin, State of Minnesota, have invented a new, original, and ornamental Design for Beverage Pot, of which the following is a specification, reference being had to the accompanying drawings, forming part thereof.

In the drawings:

Fig. 2 is a rear elevational view; and

Fig. 3 is a top plan view thereof.

The dominant features of my design reside in those portions shown in full lines.

I claim:

The ornamental design for a beverage pot, substantially as shown and described.

JOHN N. POLIVKA.
